CLOCKCASE OR SIMILAR ARTICLE

Henry Dreyfuss, Pasadena, Calif., assignor to The
E. Ingraham Company, Bristol, Conn., a cor-
poration of Connecticut

Application March 21, 1951, Serial No. 14,560

Term of patent 14 years

(Cl. D42—7)

To all whom it may concern:

Be it known that I, Henry Dreyfuss, a citizen
of the United States, residing at Pasadena, in
the county of Los Angeles and State of Califor-
nia, have invented a new, original, and orna-
mental Design for a Clockcase or Similar Arti-
cle, of which the following is a specification, ref-
erence being had to the accompanying drawing,
forming part thereof.

Fig. 1 is a perspective view of a clockcase or
similar article as seen from the front at an angle
and showing my new design;

Fig. 2 is another perspective view thereof as
seen from the rear at an angle; and

Fig. 3 is a side elevation thereof.

I claim:

The ornamental design for a clockcase or simi-
lar article, substantially as shown.

HENRY DREYFUSS.
